UNITED STATES PATENT OFFICE.

PRIMUS W. SMITH, OF JUNCTION CITY, TEXAS, ASSIGNOR OF ONE-EIGHTH TO JOHN J. BOOKHOUT AND JAMES R. BOOKHOUT, BOTH OF DALLAS COUNTY, TEXAS.

WELL-DRILLING BIT.

Application filed June 20, 1921. Serial No. 478,779.

To all whom it may concern:

Be it known that I, PRIMUS W. SMITH, a citizen of the United States, residing at Junction City, in the county of Geary and State of Texas, have invented certain new and useful Improvements in Well-Drilling Bits, of which the following is a specification.

This invention relates to new and useful improvements in well drilling bits.

The object of the invention is to provide a bit which will have a faster cutting action than the ordinary fish tail bit and which will maintain a round hole as well as a straight hole. Another object of the invention is to provide a self centering bit which may be used advantageously as a pilot drill for a larger drilling tool, but which is equally as efficient when used alone.

20 A further feature of the invention is the production of a bit in which the blades may be disassembled so as to be readily sharpened. An advantage of such a construction is a reduction in the expense of production 25 and a simple structure. Another advantage of the invention resides in the provision of means for directing a fluid, such as water, down the faces of the blade to clean the cutters.

30 Another object of the invention is to provide a bit whose blades are self sustaining by reason of the contact of their inner vertical edges throughout the entire length of the blades, whereby a lateral strain on the cutters of one blade is distributed to the other blades and the blades are braced against inward displacement.

A construction designed to carry out the invention will be hereinafter described together with other features of the invention.

40 The invention will be more readily understood from a reading of the following specification and by reference to the accompanying drawings, in which an example of the 45 invention is shown and wherein:

Fig. 1 is a view in elevation of a bit constructed in accordance with my invention and attached to a drill pipe by an ordinary collar, which latter is shown in section;

Fig. 2 is an isometric view of the upper portion of the bit with the retaining collar removed,

Fig. 3 is a cross sectional view through the head of the bit and showing the underlying blades in plan, and

Fig. 4 is a cross sectional view on the line 4—4 of Fig. 1.

In the drawings the numeral 10 designates a blade section of which three are shown as forming my bit. Each section comprises a 60 blade 11, which is disposed radially and vertically, and terminates at its lower end in a laterally directed cutter 12 curved in a 65 clock-wise direction and reduced in thickness to a cutting edge which is slightly inclined toward the center of the bit. The result of this construction is to produce a cutting point 13 at the outer edge of the cutter. Further the three cutters at the bottom of the bit will not operate on a horizontal 70 plane, but owing to the inward inclination of the cutting edges a slight conical formation will be given to the surface worked upon which will tend to center the bit. The plurality of cutting blades will prevent the 75 bit from being displaced laterally, thus assuring a round and straight hole.

Each blade section 10 is merged into a head sector 14 and these sectors when assembled produce an annular and upwardly 80 tapered externally screw threaded head which is adapted to screw into the lower end of a drill collar 15, or other connection which is usually mounted on the lower end of a drill pipe or tool shank 16. It will be 85 seen that some means must be provided for holding the blade sections together and uniting the sectors 14 in such a manner that the threads will align in proper order.

As is shown in Figs. 3 and 4, the blade sections are beveled so as to fit closely wherever they contact. It is pointed out that each blade has its entire inner vertical edge extending from end to end and substantially 90 coincident with the vertical axis of the drill. The inner edge of each blade is beveled and these beveled edges contact to brace the 95 blades, one against the other. It will be

noted that the cutting edges radiate and extend from a common point at the center of the drill. This provides continuous cutting edges across the bottom of the drill and 5 obviates cavities in which gumbo and bits of rock may lodge. One of the sectors 14 carries a dowel pin 17 which engages in a 10 socket 18 in the next adjacent sector. The third sector is provided with a pair of dowel pins 19 projecting from its diverging faces as is best shown in Fig. 3, so as to enter sockets 20 in the other two sectors when the parts are assembled. It is to be specifically understood that any suitable means may be 15 employed and the dowel pins illustrated are merely one expedient which has been found satisfactory.

Each sector 14 is surmounted by a reduced shank 21 disposed concentrically so that a 20 shoulder 22 is produced at its intersection with said sectors. These shanks are tapered and externally screw threaded so as to produce an annular screw threaded stud when the blade sections are assembled. A retaining 25 ring or collar 23 is screwed onto the stud and acts to fasten the blade sections together. The diameter of the ring is such as to leave an annular space surrounding it between said ring and the collar 15, thus 30 providing a passage for water and other fluids which pass through said collar 15. The retaining ring is merely a fastening for holding the sections together so that they may be properly screwed into the collar 15, 35 35 the engagement of the head in the collar being depended upon to hold the sections in rigid position.

In order that the blades 11, and the cutters 12 may be kept clean and thoroughly flushed, 40 water ports or courses 24 are provided in each sector 14. Each course 24 extends downwardly from the shoulder 22 to the bottom of the sector which overhangs the advance side of the blade 11, whereby the 45 water will be directed down the face of the blade and onto the cutters 12 as is obvious. The character and location of the water courses is optional and may be employed and located as found most desirable. In drilling 50 through some strata a copious supply of water is necessary, whereas in drilling through strata of a different nature very little water is necessary. The water courses are an important feature of the invention.

55 It is obvious that the cutters 12 will wear and the blades must be sharpened and new cutters formed thereon. It would be more difficult to sharpen the blades in their assembled relation in the bit. However, when 60 the bit is removed from the drill collar, it is merely necessary to unscrew the retaining ring 23 and separate the sections 10 in order to handle each blade and its cutting edge separately. By this arrangement the blades 65 may be expeditiously sharpened and reas-

sembled at a minimum expense and in a highly satisfactory manner. Further if one of the blades should be broken it can be easily replaced. It is pointed out that any desirable shape may be given to the cutters 70 12 and the invention contemplates various modifications along this line.

It is obvious that this bit will maintain its axial alignment in drilling the hole as the three blades will give it an equal bearing 75 on all sides of the hole and prevents its lateral displacement. By reason of its three cutting edges it will work much faster and function more efficiently. While I have illustrated a bit composed of three blade sections it is to be understood that the invention is not to be limited to such a number, although the best results have been had by using more than two blades or cutting edges.

What I claim, is:

1. In a deep well drilling bit, a plurality of elongated blades, each having its inner vertical edge extending from end to end and contacting with the inner vertical edges of the other blades along the vertical axis of 90 the drill, each blade projecting radially from the center of the drill and having a radial cutter at its lower edge extending from the lower end of its inner vertical edge, a segmental head sector at the upper 95 end of each blade, said sectors uniting in a cylindrical head, and means for fastening the sectors together.

2. In a deep well drilling bit, a plurality of elongated blades, each having its inner vertical edge extending from end to end and contacting with the inner vertical edges of the other blades along the vertical axis of the drill, each blade projecting radially from the center of the drill and having a 100 radial cutter at its lower edge extending from the lower end of its inner vertical edge, a segmental head sector at the upper end of each blade, said sectors uniting in a cylindrical head, and means for fastening the sectors together, each sector having a water passage 105 discharging onto the advance side of the blade.

3. In a well drilling bit, a plurality of elongated blades having their entire inner edges in contact along the vertical axis of the bit, each blade having its lower edge reduced to a cutter extending radially from the center of the bit, each cutter being inclined outwardly and downwardly from the 115 inner vertical edge of the blade, each cutter having its outer extremity curved forwardly in its direction of rotation, an integral head sector at the upper end of each blade, and means for fastening the sectors together.

4. In a deep well drilling bit, a plurality of elongated blades having their entire inner edges in contact along the vertical axis of the bit, each blade having its lower edge reduced to a cutter extending radially from 120 125 130

the center of the bit, the inner vertical edges of the blades being beveled and lying in substantially close contact, and means for fastening the blades together.

5. In a deep well drilling bit, three or more elongated blades having their inner vertical edges beveled and in contact, each

blade having its lower end reduced to a cutter which extends radially from the center of the bit, whereby cutting edges are presented entirely across the bottom of the bit, and means for fastening the bits together. 10

In testimony whereof I affix my signature.

PRIMUS W. SMITH.
